ABSTRACT OF THE DISCLOSURE

Excavating tooth components wherein the usual mating wedge faces are modified to include longitudinally extending grooves and ribs for interlocking connection so as to eliminate the need for a locking key.

Summary of invention

Since the advent of two-piece excavating teeth at least as early as 1900, there has been a continuing problem with locking the point securely on the adapter. If the lock was so secure as to completely insure connection under all types of digging, it was virtually impossible to replace the wearable point on the adapter. On the other hand, if the lock were easily releasable, there was always the possibility that the key would become removed during harsh digging with the attendant loss of the point. This would leave the adapter exposed, requiring expensive and extensive repairs to the bucket, dipper, etc., which carried the excavating tooth.

According to the instant invention, I avoid the need for any locking key, making use of novel mating parts on the component of the excavating tooth and the provision of such a component and the composite assembly constitute important objectives of this invention.

The invention is explained in conjunction with an illustrative embodiment in the accompanying drawing in which:

FIG. 1 is a perspective view of an assembled point and adapter making up an excavating tooth constructed in accordance with the teachings of this invention;

FIG. 2 is a perspective view of the components of FIG. 1 shown in disassembled condition; and

FIG. 3 is an enlarged sectional view such as would be seen along the sight line 3—3 applied to FIG. 1.

In the illustration given, the numeral 10 designates generally an excavating tooth which is seen to include an adapter 11 and a point 12. The point is considered the wearable or replaceable portion and is the part that engages rocks, gravel, etc. principally through its cutting or digging edge 13. Generally, the point 12 has a hollow-wedge shape with a socket 14 (see FIG. 2) opening to the rear of the point 12.

The adapter 11 is constructed to be mounted on the forward edge of an earth-handling device such as a dragline bucket or shovel dipper and for that purpose has a key receiving opening 15. From the forward shoulder-providing faces 16, the adapter 11 has a pair of noses 17 and 18 separated by a discrete space 19 in which a web 20 longitudinally bisecting the socket 14 is received.

The essentially corrugated nature of the interior of the socket 14 and the wedge faces of the noses 17 and 18 can be appreciated from a consideration of FIG. 3. In FIG. 3, it will be seen that a plurality of a substantially identical longitudinally extending ribs 21, 22 and 23 are provided on the upper wedge face of the nose 17. Identical ribs are provided as at 24, 25 and 26 on the lower wedge face of the nose 17. In the illustration given, the nose 18 is similarly equipped. As a specific example of the invention, the tooth pictured may be a 4.5" nominal size wherein this dimension is essentially the transverse

2

dimension of the nose assembly, i.e., the dimension ranging from the right-hand side of nose 17 to the left-hand side of nose 18. In such a case, the pitch P dimension is 0.5", the valley is 0.12", the root spacing S is 0.06", and the overall engagement height of a rib and groove is 0.31". It will be seen that a plurality of convergent planar faces are provided on the grooves and ribs of each nose and socket so as to provide a substantial frictional engagement between the point and the adapter.

In operation, the stresses encountered usually have a substantial component extending rearwardly along the mid-longitudinal plane of the assembled tooth which tends to drive the point more securely into seating engagement with the adapter noses. Because the ribs and grooves on each of the noses and the sockets are substantially identically oriented, this provides a maximum of frictional bearing so that it is extremely difficult to remove the point from the adapter. In practice, it has been found that even making use of a sledge hammer and drift pin to apply force in the direction designated F in FIG. 1 is inadequate to remove the point from the adapter. Removal, however, is facilitated by virtue of relieving a portion of the upper face of the point as at 27 for the insertion of a wedge (not shown). A wedge inserted into the relief 27 bears conjointly against the web 20 and the wall 28 defining the rearward extent of the recess 19 so that tremendous dislodging forces can be applied with a relatively small force applied to the wedge-type drift pin—thereby facilitating disengagement of the point from the adapter.

It should be appreciated that the invention here makes possible the elimination of the locking key as the means for holding the point and adapter in engagement after they have been properly joined. However, in some cases, the locking key can be used to advantage. For example, a small tooth point of a size similar to a P-2 trencher point could be very easily installed with a 2-pound hammer, and no locking key is necessary. At the other extreme, where a 200-pound point is applied to a 13" nominal size tooth, it is quite obvious that a 2-pound hammer would not have sufficient weight to provide the degree of impact that is necessary to overcome the inertia of the tooth point. Thus, unless the artisan went to approximately a 150 to 300-pound sledge hammer, it would be impossible to have the invention function and lock the components in place. In the extremely large tooth points, it will usually be necessary to install the tooth point and hold it in place with a locking key—using the power of the shovel or dragline to push the tooth point against the rock in order to properly accomplish the initial installation. From this, it can be seen that there can be no holding power attributed to the fluted bearing surface unless a sufficiently high bearing load is in existence.

From the foregoing, it will be appreciated that the degree of holding power will also depend upon the stresses encountered. Normally, very small teeth are subjected only to small stresses—hence only limited bearing is needed. In the very small types of teeth, it is possible to advantageously practice the invention with only one flute on one bearing surface.

In the illustration given, it will be noted that the flutes on the nose portion 17 and 18 extend substantially the length of the responsive noses. However, those skilled in the art realize that the fluted bearing surfaces at the tip of the nose may not be sufficiently large to keep bearing loads at a safe level under heavy beam-bending loadings. Therefore, so as to avoid the peening or crushing of various flutes, it may be desirable in some instances to terminate the flute short of the nose tip. This can be done by making a partial flute which starts as a full flute at the rear of the nose and fades out to a flat, single bear-

ing surface at the tip of the nose. In this manner, the locking power is concentrated in the rear third of the nose area, yielding maximum bearing surface where it might be needed.

By the term generally longitudinally-extending, I contemplate not only the parallel flutes depicted herein but also those that depart from substantial parallelism, i.e., slightly fan-shaped. This is possible since there is adequate clearance during installation until full mating contact is achieved.

I claim:

1. A replaceable edge part for an excavating device comprising a unitary body having a ground engaging edge at the front end thereof, said body having a longitudinal axis extending from the front end to the rear end and along which said edge part is moved for installation on an edge part holder, said body adjacent the rear end being equipped with faces adapted to mate with corresponding faces on said edge part holder, each of said body faces extending generally longitudinally of said body and being convergent longitudinally of said body, each of said body faces having a plurality of longitudinally extending spaced apart grooves therein, said grooves being parallel to each other and to said longitudinal axis, each of said grooves having substantially identical cross sectional dimensions for at least one-third of its length, and each of said grooves being defined by side walls, in the area of substantially identical cross-sectional dimensions, which side walls each form an obtuse angle with the bottom of the groove and diverge from each other as they extend from the bottom of the groove.

2. The structure of claim 1 in which said body faces are upper and lower forwardly convergent surfaces interiorly of said body to define a socket in the rear of said edge part.

3. In combination, a replaceable edge part for an excavating device and an edge part holder therefor, said edge part comprising a unitary body having a ground engaging edge at the front end thereof, said body having

a longitudinal axis extending from the front end to the rear end and along which said edge part is moved for installation on said edge part holder, said body adjacent the rear end being equipped with faces adapted to mate with corresponding faces on said edge part holder, each of said body faces extending generally longitudinally of said body and being convergent longitudinally of said body, each of said body faces having a plurality of longitudinally extending spaced apart grooves therein, said grooves being parallel to each other and to said longitudinal axis, each of said grooves having substantially identical cross sectional dimensions for at least one-third of its length, and each of said grooves being defined by side walls, in the area of substantially identical cross-sectional dimensions, which side walls each form an obtuse angle with the bottom of the groove and diverge from each other as they extend from the bottom of the groove, said edge part holder being equipped with flutes on said corresponding faces engaging the side walls of the edge part grooves.

4. The structure of claim 3 in which said body faces are upper and lower forwardly convergent surfaces exteriorly of said body to define a socket in the rear of said edge part, said edge part holder corresponding faces being upper and lower forwardly convergent surfaces defining a nose portion received in said socket.
